UNITED STATES PATENT OFFICE.

TOBIAS NEW, OF NEW YORK, N. Y.

MANUFACTURE OF PREPARED ROOFING.

SPECIFICATION forming part of Letters Patent No. 251,921, dated January 3, 1882.

Application filed November 21, 1881. (No model.)

To all whom it may concern:

Be it known that I, TOBIAS NEW, of the city and State of New York, have invented a new and useful Improvement in the Manufacture 5 of Prepared Roofing, of which the following is a clear, full, and exact description.

It is well known that prepared or ready roofing is made by putting a waterproofing composition of a gummy nature—such as the 10 pitchy products of the pine or any bituminous compound of suitable consistency to insure adhesion—between two or more layers of single saturated felt, and submitting the whole to heavy pressure in a machine. In thus manufacturing the prepared or ready roofing, the 15 resinous or pitchy connecting material is apt to ooze through from the ends of the rolls and cause the whole to stick together, and frequently to such an extent as to prevent the 20 prepared article from unrolling. It also frequently happens that the pitchy substance is pressed through the body of the felt, so that when it is applied to the roof the felt adheres firmly to the boards, and in the expansion and 25 contraction of the latter the roofing becomes cracked and consequently leaky. To overcome these serious difficulties in the prepared or ready roofing is the object of my present invention.

30 I have discovered from actual experiments that if there be rolled up with the prepared roofing when the same is being rolled for market an extra layer of felt or paper the diffi-

culty is entirely removed and a better roof is insured. I insert this extra layer in such a 35 manner that when the prepared material is unrolled upon the roof for immediate application the dry paper or felt will be next to the boarding, and as all danger of adhesion is thereby avoided, the workmen can apply the 40 roofing with greater rapidity and ease. The result is a saving of labor and securing a roof of greater durability.

I am aware that felt and other materials coated with waterproofing compounds have 45 been covered on one and both sides with paper which has been pressed on and caused to adhere to the coating of waterproofing compound; but such is not my invention.

Having thus described my invention, what 50 I claim as new, and desire to secure by Letters Patent, is—

1. An improvement in the manufacture of prepared or ready roofing, the same consisting in inserting and rolling up with the roofing a 55 layer of dry felt or paper, substantially as and for the purpose set forth.
2. As an improved article of manufacture, prepared or ready roofing provided with an extra layer of dry felt or paper, substantially 60 as and for the purpose herein described.

TOBIAS NEW.
